UNITED STATES PATENT OFFICE.

SAMSON D. WRIGHT, OF CLEVELAND, OHIO.

DUMP-CAR.

1,124,233.

Specification of Letters Patent.

Patented Jan. 5, 1915.

Application filed February 15, 1912. Serial No. 677,821.

To all whom it may concern:

Be it known that I, SAMSON D. WRIGHT, a citizen of the United States, residing at Cleveland, in the county of Cuyahoga and State of Ohio, have invented certain new and useful Improvements in Dump-Cars; of which the following is a specification.

This invention relates to improvements in dump cars generally and particularly to the body structure.

More specifically the invention is applied to cars known as coke quenching cars which are in the form of a hopper with the bottom inclined from one side to the other and with suitable openings closed by doors for discharging the material, the principal features of the invention being the bracing of the vertical supports on the discharge side of the car to prevent the swaying of the parts due to the intense weight and height of the discharge side which is subjected to great strain due to the gravitation of the load against the side resulting from the inclination of the bottom.

The invention may be more fully briefly summarized as consisting in the construction and combination of parts hereinafter set forth in the following description, drawings and claims.

Referring to the drawings, Figure 1 is a side elevation of a car of this type provided with my device; Fig. 2 is a sectional view; Fig. 3 is a detail view of the gusset members; Fig. 4 is a sectional view upon the line 4-4 of Fig. 3; and Fig. 5 is a sectional view of a brace to be used on the inside of the car.

In carrying out the invention any preferred form and construction of parts may be employed so long as they possess the necessary characteristics, but I have shown one form in the drawings which is highly effective in operation and in such embodiment 1 represents the frame or bed of the car 45 mounted upon suitable trucks 2 one of which is shown in the drawings. Secured to this bed 1 are suitable uprights 3 and 4, shown in Fig. 2, adapted to support a body floor preferably made up of cast plates 5 arranged on 50 channels 6 extending across the car. This floor is inclined from one side of the car to the other and secured to the framework of the car on the short side is a channel 7 and on the opposite side, which is the dump side 55 of the car. At intervals on this side, are vertically disposed channels 8 arranged

back to back and extending upward for a short distance where they are secured to a longitudinally disposed angle iron 8' connected to vertically disposed angles 8" to 60 which are secured upper plates 9, the plates and the angles 8 being secured to an upper angle rail 10 at the top. The ends 11 of the car are secured to one of these channels 8 in each case. These supports formed by the 65 channels 8 extend below the bottom or floor of the car for a purpose to be described. Secured in the bottom of these channels above the floor are suitable guides 12 which receive cast iron doors 13 adapted to slide in 70 these guides. Along the lower front edge of the floor of the car and underneath the same is a channel 14 secured to the floor plates and to the transverse channels 6 which support the floor and between this channel and 75 the vertically disposed channels 8 is a gusset plate 15 of substantially the configuration shown in Fig. 3 and extending below the channel 14 where it is secured to the downwardly extending portions of the channels 80 8. This forms a brace for the vertical channels 8 and tends to prevent the swaying of the side of the car. Additional means is provided for doing away with this swaying movement, and it comprises a pair of 85 cast diaphragm plates 16, shown in dotted lines in Fig. 1, in side elevation in Fig. 2, and in section in Fig. 5, and these plates are provided with meeting flanges 17 at their upper edges and lower flanges 18 to be secured to the floor of the car and side flanges 19. These plates are arranged in a manner such that they form an inverted V. The flanges 19 are firmly secured to the side 9 of the car while the flanges 18 are firmly secured to the floor, and this inverted V-shaped construction, together with the gusset 95 15, prevents the swaying or endwise movement of the entire dump side of the car, a feature which is of the greatest importance in a car of this type. This inverted V-shaped brace also prevents the outward bulging of the car side.

Having described my invention, I claim:

1. In a coke quenching car, suitable trucks, a frame supported on said trucks, and a body mounted on said frame comprising a bottom inclined from one side of the car to the other, a vertical side extending from substantially the lower edge of the bottom, 105 dumping doors in said side, and a bracing means for said side comprising a cast in-

verted V shaped member extending from the side to the bottom of the car and secured to both parts.

2. In a coke quenching car, suitable trucks, 5 a frame mounted on said trucks, a body mounted on said frame and comprising an inclined bottom extending from one side of the car to the other, suitable ends, a side extending upward from substantially 10 the lower edge of the bottom and having discharge openings, cast inverted V shaped bracing members arranged within the car

and secured to the side and the bottom, vertically disposed supports arranged at intervals along the side and extending below the 15 bottom of the car, and gussets secured to the projected ends of said braces and to the bottom of the car.

In testimony whereof I affix my signature in presence of two witnesses as follows.

SAMSON D. WRIGHT.
